DESIGN FOR A BADGE OR SIMILAR ARTICLE

Margaret Davis Cogswell, Arlington, Mass.

Application January 20, 1942, Serial No. 105,325

Term of patent 7 years

To all whom it may concern:

Be it known that I, Margaret Davis Cogswell, a citizen of the United States, residing at Arlington, in the county of Middlesex, Commonwealth of Massachusetts, have invented a new, original, and ornamental Design for a Badge or Similar Article, of which the following is a specification, reference being had to the accompanying drawing, forming a part thereof.

In the drawing:

Fig. 1 is a front elevation of a badge or similar article showing my new design;

Fig. 2 is a cross sectional view taken on line 2—2 of Fig. 1.

I claim:

The ornamental design for a badge or similar article, substantially as shown.

MARGARET DAVIS COGSWELL.
